Primary Examiner — Kevin Rudzinski(57) **CLAIM**

The ornamental design for a solar light holder, as shown and described.

DESCRIPTION

FIG. 1 is a perspective view of a solar light holder showing my new design;

FIG. 2 is a top plan view thereof;

FIG. 3 is a front elevation view thereof;

FIG. 4 is a side elevation view thereof; and,

FIG. 5 is another perspective view thereof.

The solar light, solar stick and screws shown in broken lines illustrate environmental structures and form no part of the claimed design.
